UNITED STATES PATENT OFFICE.

DAVID HAWKINS, OF BERTRAM, TEXAS.

CAR-COUPLING.

SPECIFICATION forming part of Letters Patent No. 655,229, dated August 7, 1900.

Application filed April 11, 1899. Serial No. 712,619. (No model.)

To all whom it may concern:

Be it known that I, DAVID HAWKINS, a citizen of the United States, residing at Bertram, in the county of Burnet and State of Texas, 5 have invented certain new and useful Improvements in Car-Couplers; and I do hereby declare the following to be a full, clear, and exact description of the invention, such as will enable others skilled in the art to which 10 it appertains to make and use the same.

My invention relates to improvements in car-couplers; and it consists in the novel combination and arrangement of parts, as will be hereinafter more particularly described and 15 claimed.

In the drawings, Figure 1 is a side elevation of my complete invention, showing the parts coupled and with a portion of one of the draw-heads in section. Fig. 2 is a top plan 20 view of the same with one of the draw-heads in section, showing the location and arrangement of the ends of the links within the draw-heads; and Fig. 3 is a detail front elevation of the coupling-pin which I employ in carrying 25 out my invention.

The object of my invention is to construct a simple, practical, and durable car-coupler and, further, one that will automatically couple the cars notwithstanding the variation of 30 the heights of the same; and it consists of the combination and arrangement of parts, as will be hereinafter more specifically described in detail.

Referring to the drawings, 11 represent the 35 draw-heads, which are similarly constructed and attached to a car in the well-known manner. The draw-heads and parts accompanying the same are constructed alike, and consequently I shall only proceed to describe one 40 of the same.

Formed in one side of the draw-head 1 is a cavity 2, opening from the front of the said draw-head, within which is located one end of a link 3, having a solid portion 4, to which is 45 pivotally secured a chain 6, loosely passing through an opening 7 formed in the draw-head, the said chain extending downwardly a sufficient distance and having at its lower end a disk or washer 8, and encircling said chain 50 and interposed between the disk and the lower surface of the draw-head 1 is a spiral spring

9, which operates to hold the free end of the link 3 in a substantially-horizontal position and, further, to allow the said link to yield sufficiently upwardly and downwardly after the 55 cars have been coupled or in coupling the same. Passing through the draw-head 1 and the cavity portion 2 thereof is a pin 10, which passes through the link 3 and operates to rigidly secure the said link to the draw-head or 60 prevent the same from being withdrawn therefrom. Formed in the opposite side of the draw-head is a second and deeper cavity 11, which also opens from the front of said draw-head, the upper and lower walls of which 65 are provided with alining elongated slots 12 for the reception of the pivotally-mounted gravity-operating coupling-pin 13, whereby the latter is free to swing in the line of the slot when struck by the free end of the link 70 3 of the opposite coupler, in which operation the lower end of the pin 13 will be swung rearwardly and raised sufficiently above the bottom of the cavity 11 to allow the same to drop through the link and between the longitudinal walls of the lower slot 12, and thereby 75 couple the draw-heads.

Secured to the upper surface of the draw-head and projecting upwardly therefrom over the forward end of the slot 12, formed in the 80 upper surface of said draw-head, is a standard 14, which is formed by the employment of two U-shaped rods, the lower ends of which are secured to the draw-head, said rods being separated a suitable distance apart to form a 85 vertical guide 15, which loosely receives the opposite ends of the cross-pin 16 of the coupling-pin 13, whereby the latter is not only pivoted or hinged to the draw-head, but is 90 guided in a vertical direction within the draw-head. When it is desired to release the link 3, the said coupling-pin is elevated by a rope or chain 17, the lower end of which is attached to the upper end of said coupling-pin. One of the U-shaped bars which form the standard 14 is provided with a terminal centrally-arranged coil 18, through which the chain 17 passes, said coil being disposed substantially in a horizontal plane, and the upper or medial portion of the other U-shaped bar which forms 95 the standard 14 is also bent in a substantially-horizontal position, whereby a stop is formed 100

for the upward movement of the coupling-pin 13, and, further, forming a guide for holding the chain 17 in its proper position for elevating the said coupling-pin.

5 Having fully described my invention, what I claim is—

1. A car-coupler, comprising a draw-head having a cavity formed on one side of the same, a link located within the said cavity, and having a solid portion, a pin passing through the draw-head, and through said link, a chain having its upper end attached to the solid portion of said link, and passing through an opening formed in the draw-head, a washer fixed to the lower end of said chain, a coiled spring encircling said chain, and interposed between the lower surface of the draw-head and washer, the opposite side of said coupler also being provided with alining slots, a standard forming a guide secured to the upper surface of the draw-head above the forward end of the slot formed in the upper wall thereof, a coupling-pin passing through said slots, a cross-pin secured to the said coupling-pin, the opposite ends of which are received by said guide, and a chain or rope attached to the upper end of said coupling-pin,

for elevating the latter, as and for the purpose described.

2. A car-coupler, comprising a suitable draw-head, a link yieldingly secured at one side of the same, a cavity formed in the opposite side of said draw-head, and having alining slots formed in the upper and lower walls thereof, a guide secured to the upper surface of the draw-head, and composed of two U-shaped bars separated a suitable distance apart, a coil formed in the upper or medial portion of one of said bars, and arranged in a substantially-horizontal position, the upper medial portion of the other bar being also bent in a substantially-horizontal position, a coupling-pin normally located within the slots formed in the draw-head, a cross-pin carried by the said coupling-pin, the free ends of which are normally located between the bars which form the guide, and a rope or chain attached to the upper end of the coupling-pin, and passing through the coil formed in one of said bars, as and for the purpose described. 50

DAVID HAWKINS.
